UNITED STATES PATENT OFFICE

2,605,583

CURTAIN RACK OR STRETCHER

Victoria M. Owens, Baltimore, Md.

Application April 30, 1951, Serial No. 223,696

2 Claims. (Cl. 45—24)

1

This invention relates to curtain racks or stretchers.

An object of this invention is to provide a rack embodying extensible frame members which are preferably made out of channel material and the channel frame members include retractable and extensible pins so that the frame may be set up without injury to the hands.

Another object of this invention is to provide improved pin bars and means for extending or retracting the pins.

A further object of this invention is to provide a curtain rack wherein the frame members may be inserted in the hems of curtains or other fabric without the use of pins.

With the above and other objects in view, my invention consists in the arrangement, combination and details of construction disclosed in the drawings and specification, and then more particularly pointed out in the appended claims.

In the drawings:

Figure 1 is a detailed front elevation of a curtain stretcher constructed according to an embodiment of this invention.

Figure 2 is a fragmentary rear elevation of the device.

Figure 3 is an end elevation of the device.

Figure 4 is a fragmentary sectional view taken on the line 4—4 of Figure 1.

Figure 5 is a fragmentary sectional view taken on the line 5—5 of Figure 1.

Figure 6 is a fragmentary sectional view taken on the line 6—6 of Figure 1.

Figure 7 is a fragmentary sectional view taken on the line 7—7 of Figure 1.

Figure 8 is a fragmentary sectional view taken on the line 8—8 of Figure 2.

Figure 9 is a fragmentary sectional view taken on the line 9—9 of Figure 1.

Figure 10 is a fragmentary sectional view taken on the line 10—10 of Figure 1.

Figure 11 is a fragmentary rear elevation of the device.

Figure 12 is a front elevation of a modified form of intermediate stretcher bar.

Referring to the drawings, the numeral 15 designates generally a frame structure which is formed of end bars 16 and 17, an upper horizontal bar 18, and a lower horizontal bar 19. The bars 16 to 19 are of channel shape, being constructed out of metal, and the upper bar 18 is fixed to the end bars 16 and 17 by means of L-shaped members 20. In the present instance there are disclosed two of these frame members 15 disposed in end abutting relation and coupled

2

together so as to form a relatively long stretcher frame construction. The frame 15 is supported in upstanding position inclined to the vertical by means of a pair of leg supports 21 formed by bending a relatively stiff bar upon itself, and the upper ends of the leg members 21 are pivotally mounted in apertured lugs 22 carried by the end frame members 16 and 17.

Where two of these frame members or units are disposed in alignment the intermediate support 21 is coupled to the abutting inner end members 17 as shown in Figures 1 and 2. The lower channel member 19 is vertically adjustable on the end members 16 and 17 and is secured in adjusted position by means of a hook shaped bolt 23 as shown in Figure 10 which is engageable over one side of the end member 17, and a wing nut 24 is threaded onto the bolt 23.

The opposite or outer end of the channel member 19 as shown in Figure 6 has projecting therefrom an L-shaped extension 25 terminating in a hook 26 engageable over the outer side wall 27 of the end member 16. The outer side wall 27 as shown in Figure 3 is formed with a plurality of spaced apart openings 28 within which a threaded bolt 29 is adapted to engage. A pair of vertically disposed intermediate channel bars 30 engage between the horizontal bars 18 and 19 and are adjustable along the length of the latter.

The intermediate channel members 30 at their upper ends are formed with extensions 31 terminating in a hook 32 engageable over the upper side 33 of the upper frame member 18. A set screw 34 is threaded through the extension 31 and bears against the upper side 33 so as to secure the upper end of the channel member 30 in adjusted position along the length of the upper member 18.

The lower portion of the intermediate bar 30 is adjustably secured along the length of the lower channel member 19 by means of an L-shaped clamping member 35 having an outer plate 36 confronting the outer side of the channel member 30, and the clamping member 35 is formed with a hook 37 engageable over the lower wall or side 38 of the channel member 19.

A set screw 39 is threaded through the outer wall or jaw of the clamping member 35 and bears against the channel member 30. The upper and lower channel members 18 and 19 are provided with elongated slots 40 within which pins 41 are adapted to loosely or slidably engage.

The pins 41 are secured to an elongated pin carrier 42 disposed within the channel of the frame member, and the carrier 42 is adapted to

be moved forwardly to extended position or rearwardly to retracted position by means of a cam shaft 43.

The carrier 42 has secured thereto a pair of straps 44 engaging about the cam shaft 43 so that the carrier 42 will move forwardly or rearwardly with rotation of the shaft 43. The opposite ends of the shaft 43 are provided with studs 45 engaging through bearings 46 carried by the channel member and a handle or lever 47 is secured to one of the studs 46 so that the shaft 43 may be manually rotated.

Each intermediate channel member 30 is also formed with an elongated opening or slot 48 within which pins are adapted to loosely and slidably engage, and a pin carrier similar to carrier 42 is disposed within the channel 30 and is movable forwardly or rearwardly by means of an eccentric shaft 43.

The upper frame member 18 has secured thereto a pair of hooks 49 which are swivelly or rotatably secured to the upper frame member 18 so that, if desired, the frame structure may be suspended from a suitable support.

Referring now to Figure 12 there is disclosed a modified form of intermediate channel frame member 50 which is similar in every detail to the intermediate channel frame members 30 with the exception that the channel member 50 does not have the pins and pin carrier and is adapted to be inserted within a hem or the like of a curtain or other fabric which is to be stretched.

In the use and operation of this stretcher the frame structure 15 is initially set up in upstanding position by extending the legs 21 rearwardly at their lower ends as shown in Figure 2. The intermediate channel members 30 are adjusted along the horizontal channel members 18 and 19, and after the initial adjustment of the intermediate members 30 and the lower member 19 the pins 41 of the horizontal and vertical or intermediate channel members may be moved forwardly to extended and operative position.

The curtain or fabric is then engaged with the extended pins in the normal manner. The frame structure hereinbefore described is adapted to be made out of relatively light weight metal, such as aluminum or the like, and will provide a rigid frame structure which will withstand the normal usage for a device of this kind.

By providing the retractable and extendible pins, the person setting up the stretcher will not be injured by the pins during the setting up operation.

5 What is claimed is:

1. A curtain stretcher comprising a frame formed of a pair of end bars, upper and lower horizontal bars, a pair of vertical intermediate bars, means adjustably securing said intermediate bars to said upper and lower bars, said upper, lower and intermediate bars being of channel shape and each of said latter named bars having spaced openings longitudinally thereof, a pin carrier loosely disposed between the sides of each of said channel bars, pins fixed to said carrier engaging in said openings, and means comprising an eccentric shaft carried by said carrier, and an extending knob for turning said shaft for shifting said pin carrier to thereby extend or retract said pins.

2. A curtain stretcher comprising a frame formed of a pair of end bars, an upper channel bar fixed to said end bars, a lower channel bar, means adjustably securing said lower bar to said end bars, a pair of intermediate channel bars, means adjustably securing said intermediate bars to said upper and lower bars, a pin carrier within the channel of each channel bar, a plurality of pins carried by said carrier, each channel bar having openings through which said pins slidably engage, an eccentric shaft rotatably carried by each channel bar, means for rotating said shaft, and means carried by said carrier engaging about said shaft whereby said carrier and pins will be adjusted to retracted or extended position upon rotation of said shaft.

VICTORIA M. OWENS.
